DESIGN FOR A COMBINED KNIFE RACK
AND SHARPENER

Edmund P. Kampa, Thiensville, Wis.

Application March 6, 1947, Serial No. 137,413

Term of patent 14 years

(Cl. D44—29)

To all whom it may concern:

Be it known that I, Edmund P. Kampa, a citizen of the United States, residing at Thiensville, in the county of Ozaukee and State of Wisconsin, have invented a new, original, and ornamental Design for a Combined Knife Rack and Sharpener, of which the following is a specification, reference being had to the accompanying drawing, forming a part thereof.

Figure 1 is a perspective view of a combined knife rack and sharpener showing my new design.

Figure 2 is a side view showing the sharpener in the open position, and

Figure 3 is a similar side view thereof with the sharpener in a closed position.

I claim:

The ornamental design for a combined knife rack and sharpener, as shown.

EDMUND P. KAMPA.
